ANCHOR

John K. Northrop, Santa Barbara, Calif., assignor to The Garrett Corporation, Los Angeles, Calif., a corporation of California

Application June 25, 1956, Serial No. 593,740

8 Claims. (Cl. 114—207)

This invention relates generally to anchors; it is more particularly directed to anchors having relatively movable parts which may be disposed in certain positions to place the device in condition for stowing or other positions to condition the device for active use.

An object of this invention is to provide an anchor composed primarily of stamped or otherwise suitably formed pieces assembled by welding or other well-known method to produce a simple, compact unit which will render efficient service and be convenient to store when not in use.

Another object of the invention is to provide an anchor having a body with a shank and a crossbar at one end thereof to support angularly directed, ground penetrating flukes, the body having means for receiving a stock member for adjustment between two positions in one of which the stock member is at right angles to the body and crossbar and in the other position the stock member is parallel to the body shank, suitable holding means being provided to retain the stock member in each of such positions.

Another object of the invention is to provide an anchor of the type mentioned in the preceding paragraph and in which the body of the anchor has a first means receiving the stock member for sliding movement and a second means operative when the stock member has reached a predetermined position of movement to provide an axis about which the stock member may be swung to cause it to assume a position parallel to the shank of the anchor body, the holding means mentioned in the preceding paragraph retaining the stock member in the latter position and in a certain position assumed during sliding movement in the first means.

A further object of the invention is to provide an anchor having a body with a sheet metal shank and crossbar, the body having guide means shaped to slidably receive a channel-shaped stock member, the body also having a projection extending into the guide means and engaging a bar on the stock member during movement thereof in the guide means, the engagement of the bar and projection interrupting the sliding movement of the stock member and providing for swinging movement thereof to a position parallel with the shank, fastening means being provided on the stock member and the body to retain these elements in both operative and stowing conditions.

A still further object is to so construct the anchor mentioned in the preceding paragraph that the guide means forms the twofold purpose of guiding the stock member in its sliding movement from an active position toward an inactive position and holding one end of the stock member against lateral movement when the latter is in an inactive position, interengaging means being provided on the body and the intermediate portion of the stock member to retain the rest of the stock member against movement when in the inactive position.

Other objects and advantages will be apparent from the following description and the accompanying draw-

2

ings in which one embodiment of the invention has been illustrated in detail.

In the drawings:

Fig. 1 is a perspective view of an anchor formed in accordance with the present invention, the parts being disposed in positions occupied when the anchor is in condition for stowing;

Fig. 2 is a similar view showing the parts in the positions occupied when the anchor is in condition for operation;

Fig. 3 is a detailed sectional view taken on the plane indicated by the line 3—3 of Fig. 1, and

Fig. 4 is a fragmentary elevational view of the bottom of the anchor shown in Fig. 3.

15 A closer inspection of the drawing will disclose that the embodiment of the invention selected for illustration includes two major parts 10 and 11, one part 10 being hereinafter termed the body of the anchor and including a shank 12 and a crossbar 13 secured to one end 20 of the shank by welding or other suitable method of attachment indicated at 14. The shank and crossbar are formed of sheet or plate material, the crossbar terminating at its ends in angularly directed, tapered extensions 15. These extensions have triangular plates 16 welded 25 thereto, the angular extensions and plates forming flukes which are adapted to penetrate the soil, sand, or other surface to be engaged thereby during the use of the device.

The shank 12 has a link 17 at the end opposite that 30 carrying the crossbar to receive a chain, cable, or other suitable means, for attaching the anchor to the boat or other vehicle.

Adjacent the point of attachment of the stock and shank to one another, the crossbar is provided with a 35 guide element 18 which is also formed of sheet or plate material having a curved central portion which terminates in spaced legs 19 having slots formed therein to permit the legs to straddle the crossbar. These legs are secured by welding to the sides of the crossbar to retain the guide member 18 in place thereon.

40 The guide member is provided for the reception of part 11, which is hereinafter termed the stock member of the anchor, this member being provided for the purpose of preventing the anchor from lying flat on the ground when it is placed in use. The stock causes the anchor to turn until one or the other of the flukes engages the ground and penetrates the same to hold the vessel.

45 The stock member 11 in the present form of the invention is also formed of sheet or plate material, being of strip form and bent transversely into a modified channel-shaped cross section which corresponds substantially to the shape of the guide 18. The latter receives the stock member for longitudinal sliding movement and serves, 50 when the stock member is disposed therein, to retain this member in a position at right angles to the shank and the crossbar. When the anchor is in condition for use, the stock member is located with its central portion in the guide member so that equal parts of the stock project from either side of the crossbar. It is retained in this position by a flexible spring 20 formed of a length of wire doubled upon itself and clamped to the stock member with a retainer 21 and screws, or other fastening elements, 55 22.

60 The intermediate portions of the wire projecting from the point of attachment to the stock member, are bent as at 23 to provide finger-engaging portions through the use of which the spring may be flexed to release the stock member from its active position so that it may be moved to another position which it occupies when the anchor is 65 in condition to be stowed. The ends of the spring are bent outwardly to provide hooks 24 for engagement with 70

spaced ears 25 provided on the guide member 18, this member being recessed as at 26 to form the ears and to receive the hook members 24. When the stock member is being placed in operative condition, one end thereof is inserted in the guide member. Then the stock member is moved longitudinally until the hooks 24 engage the rounded portions of the ears 25. Continued movement of the stock member will flex the hooks until they snap into place behind the ears and retain the stock member in operative position. The arrangement of the hooks and ears in this position is shown in Fig. 2.

One of the features of the invention is the folding or adjustment of the anchor for stowing purposes. To secure this feature, the stock member has a bar 27 secured thereto in such a manner as to extend between the sides of the channel at one end of the stock. The shank, or crossbar, adjacent its point of attachment to the shank is provided with one or more small pieces 28 which project at one end into the guide member for engagement with the bar 27 when the stock is moved outwardly of the guide. This engagement of the bar with the projections 28, the latter being hereinafter termed hooks, provides an axis for swinging movement of the stock member to a position at one side of the shank 12. In this position, the stock is substantially parallel and co-extensive with the shank, and the anchor is reduced in effective size to facilitate stowing thereof.

To retain the anchor in its folded condition, the stock member has an opening 29 provided therein, this opening being disposed in registration with the space between the ends of the spring 20. The opening is provided to receive a stud 30 which projects from the side of the shank 12. The stud has a groove 31 at a point adjacent the free end so that a head 32 will be provided. When the stock is swung to the stowing position, the head end of the stud will pass through the opening 29, and the spring ends will ride over the head and be disposed in the groove 31 to retain the stock in folded condition. It will be noted that the open side of the channel-shaped stock member faces the shank; and when it is desired to place the anchor in condition for operation, the user may insert one or more fingers into the end of the stock and by a pulling force, release the spring from the stud. The stock may then be swung about the axis provided by the engagement of the bar 27 with the hooks 28 until the end of the stock is aligned with the guide 18. The stock may then be moved longitudinally into the guide until the spring hooks engage the ears 25. It should be noted that the distance from the bar 27 to the hole or opening 29 corresponds substantially with the distance between the hooks 28 and the stud 30. This arrangement causes the opening 29 to register with the stud 30 near the termination of the swinging movement of the stock and insures convenience in the operation of folding the stock member.

It will be noted that the legs 19 of the guide 18 serve to locate the end of the stock member and prevent lateral movement thereof when the stock is disposed at the side of the shank and the stud 30 is positioned in the opening 29.

I claim:

1. An anchor comprising a body having a shank portion with a crossbar at one end; fluke means at the ends of said crossbar; a stock member; guide means on said body receiving and holding said stock member in a first position at right angles to said shank and said crossbar, said guide means providing for sliding and swinging movement of said stock member from said first position to a second position substantially parallel with said shank portion; finger means on said guide means and spring means on said stock member for locking said stock member in said first position; and means on said shank for engaging said spring means to lock said stock member in said second position.

2. An anchor comprising a body having a shank portion with a crossbar at one end; fluke means at the ends

of said crossbar; a stock member; guide means on said body, said stock member being slidably in said guide means and held thereby in a first position at right angles to said shank and said crossbar; said stock member being held in said first position by latch means carried by said stock member; means on said stock member and said body for interengagement to provide for swinging movement of said stock member to a second position substantially parallel with said shank portion; and means on said body engaging said latch means on said stock member for locking said stock member in said second position.

3. An anchor comprising a body having a shank portion with a crossbar at one end; fluke means at the ends of said crossbar; a stock member; guide means on said body, said stock member being longitudinally slidably in said guide means and held thereby in a first position at right angles to said shank and said crossbar; means adjacent said guide means for engagement by a portion of said stock member to provide for swinging movement of said stock member to a second position at the side of and substantially parallel to said shank; a pair of opposed fingers formed on said guide means; spring means secured to said stock member, said spring means being disposed to engage said fingers to lock said stock member in said first position; and pin means on said shank disposed to engage said spring means to lock said stock member in said second position.

4. An anchor comprising a body having a shank portion with a crossbar at one end; fluke means at the ends of said crossbar; a stock member having holding means disposed on a face thereof; guide means on said body, said guide means being shaped to slidably receive said stock member and to engage said holding means to retain said stock member in a first position at right angles to said shank and said crossbar; hook means adjacent said guide means disposed to engage an end portion of said stock member and providing for swinging movement thereof to a second position at the side of and substantially parallel to said shank; and catch means on said body adapted to cooperate with said holding means on said stock member for locking said stock member in said second position.

5. An anchor comprising a body having a shank portion with a crossbar at one end; fluke means on said crossbar; a stock member having a channel-shaped cross section; guide means adjacent the juncture of said shank and crossbar for slidably receiving and holding said stock member in a first position at right angles to said shank and said crossbar; means extending transversely of said channel-shaped stock member adjacent one end thereof; means adjacent said guide means to engage the transversely extending means on said stock member and provide for swinging movement of the latter to a second position substantially parallel with said shank; a pair of opposed fingers formed on said guide means; pin means secured on said shank; and spring means on said stock member disposed to respectively engage said fingers and said pin means to hold said stock member in each of said positions.

6. An anchor comprising a body having a shank portion with a crossbar at one end; fluke means on said crossbar; a stock member having a channel-shaped cross section; guide means adjacent the juncture of said shank and crossbar for slidably receiving and holding said stock member in a first position at right angles to said shank and said crossbar; means extending transversely of said channel-shaped stock member adjacent one end thereof; hook means adjacent the juncture of said shank and crossbar for engaging the transversely extending means on said stock member and providing a pivotal axis for swinging movement of the stock member to a second position substantially parallel with said shank; and interengaging means having portions on said stock member, said shank and said guide means for holding said stock member in each of said positions.

7. An anchor comprising a body having a shank portion with a crossbar at one end; fluke means on said crossbar; a stock member having a channel-shaped cross-section; guide means on said body, said guide means being shaped to conform to the cross-sectional configuration of said stock member and receive the same for longitudinal sliding movement, said guide means serving to hold said stock member in one position at right angles to said shank and said crossbar; a bar extending transversely of said channel-shaped stock member at one end; a hook member disposed on said body and projecting into said guide means to engage the bar on said stock member at one extremity of longitudinal movement of said stock member and provide an axis for swinging movement thereof to a second position substantially parallel to said shank, said guide means preventing lateral movement of one end of said stock member in the second position; and means on said body engaging the intermediate portion of said stock member to hold the same in said second position.

8. An anchor comprising a body having a shank portion with a crossbar at one end; fluke means on said crossbar; a stock member having a channel-shaped cross-section; guide means on said body, said guide means being shaped to conform to the cross-sectional configuration of said stock member and receive the same for longi-

tudinal sliding movement, said guide means serving to hold said stock member in one position at right angles to said shank and said crossbar, the open side of said channel-shaped stock member facing said body in said one position; a bar extending across the open side of said channel-shaped stock member; a hook member on said body and projecting into the open side of said channel-shaped stock member, said hook member engaging the bar on said stock member at one extremity of longitudinal movement of said stock member and providing an axis for swinging movement thereof to a second position substantially parallel to said shank, the open side of said stock member facing said body in said second position; and interengaging means on said body and said stock member for holding the latter in each of said positions.
